UNITED STATES PATENT OFFICE.

EDWIN L. HENDERSON, OF NORWOOD, OHIO, ASSIGNOR TO THE KEMPER-THOMAS COMPANY,
OF NORWOOD, OHIO, A CORPORATION OF NEW JERSEY.

SUIT-HANGER.

No. 901,002.

Specification of Letters Patent.

Patented Oct. 13, 1908.

Application filed July 20, 1908. Serial No. 444,433.

To all whom it may concern:

Be it known that I, EDWIN L. HENDERSON, a citizen of the United States, residing in Norwood, in the county of Hamilton and 5 State of Ohio, have invented certain new and useful Improvements in Suit-Hangers, of which the following is a full, clear, and exact description, reference being had to the accompanying drawings, forming part of 10 this specification.

The purpose of my invention is to provide an exceedingly light, cheap and durable coat and suit hanger, which shall at the same time furnish ample surface for the display 15 of advertising matter without in any way detracting from the utility of the construction as a hanger.

The body of the hanger is therefore formed from paper tubing of diameter sufficient to furnish a suitable space around the tube for advertising matter, while at the same time, a strong and light form is provided for the support of the coat, and in connection with which a hanger for trousers 25 can be readily secured.

In the drawings: Figure 1 is a perspective view of my improved hanger ready for use. Fig. 2 is a perspective view of the various parts from which the hanger is constructed. 30 Fig. 3 is a central vertical section of the hanger.

Two short cylinders of wood 1 and 2 are cut on a bevel and secured together by a dowel pin 3 to form an obtuse angle with 35 each other. Paper tubes 4 and 5 of suitable length, and correspondingly beveled at their meeting edges, are provided of a diameter to fit snugly over the wood cylinders to which they are secured, by gluing or otherwise, to make a substantial and durable form 40 for the support of a coat.

6 is a wire rod which is driven through the central portion of the wood cylinders at the apex of the cylinders and this wire is 45 suitably bent to form a hook 7 for the support of the hanger. Paper disks 8, 8 with a central eyelet 9 are glued into the outer open ends of the tubes to stiffen the tubes at the outer ends and also to serve as a means of 50 attachment for the trousers hanger. This trousers hanger comprises a rod 10, of wood or other suitable material, and the rod is se-

cured in place as shown in Fig. 1 by the hooks 11, 11, one end of each hook being bent to pass through the ends of the rod 10, and 55 the other end being so bent at 12, as to hook within the eyelet 9, thus holding the rod 10, securely in position. By thus making use of paper tubing for the hanger form, with a solid wooden cove at the middle for joining the tubes together and reinforcing the outer ends of the tubing by the disks, an exceedingly strong and durable form is provided which at the same time is light and 60 easy of construction.

65 The large size of the tubing fills out the shoulders of the garment, preventing sagging and wrinkling, at the same time the surface of the tubing gives ample space for advertising matter of the party furnishing 70 the hanger.

Having thus described my invention what I claim as new and desire to secure by Letters Patent, is:

1. In a device of the character specified, a 75 core of wood, comprising beveled plugs secured together at an obtuse angle, and tubes of paper material secured on said plugs to form an angular frame for a coat support, and hook for suspending the hanger mounted in said core.

2. In a device of the character specified, a pair of tubes of paper material, with means for securing said tubes together at an obtuse angle to form a coat supporting frame, and 85 a rod extending between the outer ends of said tubes with hooks secured to said rod and engaging the ends of the tubes to hold the rod in place.

3. In a device of the character specified, a 90 pair of tubes of paper material, means for securing said tubes together at an obtuse angle to form a coat supporting frame, disks secured in the outer ends of said tubes to strengthen and support the tubes, said disks 95 having central eyelets, a rod extending between the outer ends of said tubes and hooks secured to the ends of said rod and engaging the disk eyelets to hold the rod in place.

EDWIN L. HENDERSON.
